UNITED STATES PATENT OFFICE

93,731

DESIGN FOR AN AIRPLANE

Lessiter C. Milburn, Towson, Md., assignor to The
Glenn L. Martin Company, Baltimore, Md.

Application January 6, 1934, Serial No. 50,336

Term of patent 14 years

To whom it may concern:

Be it known that I, LESSITER C. MILBURN, a citizen of the United States, residing at Towson, in the county of Baltimore and State of Maryland, have invented a new, original, and ornamental Design for an Airplane, of which the following is a specification, reference being had to the accompanying drawings, forming part hereof.

Fig. 1 is a perspective view of the subject airplane in flight; and

Fig. 2 is a similar view of the same airplane, but differing therefrom in angularity.

Fig. 3 is a top plan view of the airplane shown in Figures 1 and 2.

Fig. 4 is a front view of the subject airplane when the landing wheels are extended for ground engagement; and

Fig. 5 is a side view of the same airplane when the landing gear, including the wheels, is retracted in flight.

Fig. 6 is a view similar to Figure 5, but showing the subject airplane, with the wheels, in position for taking off or alighting.

The dominant features of my design are the streamlined fuselage surface of revolution, the observation windows forming portions of that surface, and the relation of that surface to the high mounted wings, as shown in the accompanying drawings.

I claim:

The ornamental design for an airplane as shown and described.

LESSITER C. MILBURN.
